IGNITION SYSTEM USING PLURAL
STARTING SWITCHES

Russell J. Langlois, 697 Lafayette Ave., Uniondale, N.Y.
Filed Oct. 11, 1961, Ser. No. 147,395
2 Claims. (Cl. 307—10)

This invention relates to ignition systems and more particularly to means by which a motor-vehicle ignition system must first be prepared for use before the usual starter-and-ignition switch may be operated to start the motor and by which the motor may be started independently of the usual starter-and-ignition switch.

The invention (although capable of other uses) has, therefore, for a primary object to provide a device to be connected with or "cut into" the ignition circuit of a motor-vehicle ignition system with the capacity to close its portion of the ignition circuit before the usual starter-and-ignition switch can be operated to start the motor.

Another object of the invention is to provide such a device with the capacity to start the motor independently of the usual starter-and-ignition switch.

A further object of the invention is to provide, as a separate article of manufacture, a unit adapted to be connected with or "cut into" the ignition circuit of a motor-vehicle ignition system with the capacity for preparing the ignition system for a motor start by the usual starter-and-ignition switch and the capacity to start the motor independently of this switch.

The foregoing and other objects of the invention will best be understood from the following description of a preferred embodiment thereof illustrated in the accompanying drawings in which:

FIG. 1 is a wiring diagram of a motor-vehicle ignition system embodying the present invention;

FIG. 2 illustrates the device of the invention, the view being a vertical section taken substantially on the line 2—2 of FIG. 3;

FIG. 3 is a vertical section taken substantially on the line 3—3 of FIG. 2;

FIGS. 4 to 7 inclusive are diagrams showing successive steps in the operation of the starter-and-ignition switch of the device as it cooperates with and as it is operated independently of the conventional switch;

FIGS. 8 and 9 are wiring diagrams of the primary and secondary ignition circuits respectively;

FIG. 10 shows the device applied to the ignition system of a front-engine vehicle; and

FIG. 11 shows the device applied to the ignition system of a rear-engine vehicle.

Referring to the wiring diagram shown in FIG. 1, at 20 is indicated the battery which is grounded at 21. At S¹ is the usual normally-open key-operated starter-and-ignition switch which is mounted on the instrument panel 65 of the vehicle (see FIG. 10). The switch S¹ is of the usual well known construction having terminals 2, 3, 4 and 5. The switch S¹ is operated by a key 6. At 22 is the ignition coil which comprises primary and secondary windings 23 and 24 respectively. At 25 is the circuit breaker and at 26 the distributor. At 27 is the starter motor and at 28 is indicated the usual solenoid switch, the coil of the solenoid being grounded at 29. At 30 is the generator which is grounded at 31. At 32 is the generator regulator.

All of the above designated ignition units or components are well known from long usage in the ignition art and form no part of the present invention except in so far as they co-operate therewith to produce the desired results.

Referring now to FIGS. 2 and 3, there are shown two sectional views of the device embodying the present invention. This device indicated at D (see also FIGS. 1, 10 and 11) includes a normally-open key-operated starter-and-ignition switch S² (see also FIGS. 4 to 7 inclusive)

2

and a pilot light 40 which is connected therewith and lighted thereby to indicate a closed circuit whenever this switch is operated.

These components are mounted in a casing 41 which is located in the motor compartment 42 of a front-engine car (FIG. 10) or in the motor compartment 42' of a rear-engine car (FIG. 11) in accordance with one feature of the invention to be hereinafter described. The casing 41 is preferably secured to the fire wall of either type car by 10 screws 43.

The switch S² comprises a triangular current-conducting switch element 7 which is provided with three contact points one of which is clearly indicated in FIG. 2. The switch element 7 is carried by a rotatable member 8, upon 15 which it is slidably mounted (see particularly FIGS. 2 and 3). The member 8 and consequently the switch element 7 are rotated by a key 9 through a key member 10. At 11 is indicated a fixed non-conducting switch element in which are embedded switch terminals 12, 13, 14 and 15. 20 The contact points of the switch element 7 are adapted to be rotated in the path of said terminals and are pressed against the switch element 11, and consequently against the terminals 12, 13, 14 and 15, by a spring 45 (FIG. 2).

Connected with the switch terminals 12, 13, 14 and 15 25 are conductors or wires 16, 17, 18 and 19 respectively. For convenience and a clearer understanding of the wiring arrangement the conductors 16, 17, 18 and 19 are further designated by the follow-inscriptions: yellow, red, black and blue respectively. These conductors are of pre-determined variable lengths sufficient to reach the ignition units or junction points in the ignition wiring with which 30 they are intended to be connected. The pilot light 40 is connected by a wire 46 with the switch terminal 15 and is grounded by a wire 47 to the casing 41.

35 Returning to FIG. 1, the connection of the wires 16, 17, 18 and 19 of the starting-and-ignition switch S² to the conventional type ignition system shown in this figure of the drawings will now be described. The yellow wire 16 is connected with the wire 53 coming from the terminal 4 of the switches S¹; the red wire 17 is connected with the terminal 80 of the generator regulator 32; the black wire 18 is connected with the solenoid switch 28; and the blue wire 15 is connected with the primary winding 23 of the ignition coil 22.

40 The present invention thus provides two interconnected ignition circuits comprising a primary ignition circuit in which both starter-and-ignition switches S¹ and S² are involved (see particularly FIG. 8) and a secondary ignition circuit in which the starter-and-ignition switch S² is 45 involved (see particularly FIG. 9).

When the motor is to be started from the instrument panel of the vehicle the key 9 is first inserted in the switch S² of the primary ignition circuit and turned in a counter-clockwise direction to rotate its switch element 7 from the 55 position shown in FIGS. 1, 3 and 4 to the position shown in FIGS. 5 and 8. This connects the yellow wire 16 with the blue wire 19 to close the portion of the ignition circuit that is directly associated with the switch S².

The switch S¹ is then operated in the usual manner by 60 turning its key 6 in a clockwise direction to a first position shown in FIG. 8 to close its portion of the ignition circuit. This completely closes the primary ignition circuit (see particularly FIG. 8) and permits the current from the battery 20 to flow through wire 50, solenoid switch 28, wire 52, switch S¹, wire 53, yellow wire 16, switch element 7 of the switch S², blue wire 19, primary winding 23 of the coil 22, wire 48, circuit breaker 25 and to ground at 54. This lights the pilot light 40 and puts the ignition system 65 in condition for a motor start from the instrument panel of the vehicle. It will be apparent from the operation of the system so far described that the switches S¹ and S² are

arranged in series in the primary ignition circuit in accordance with one feature of the present invention.

The key 6 of the switch S¹ is then advanced to a second position to start the motor. This permits the current from the battery 20 to flow through wire 50, solenoid switch 28, wire 52, switch S¹, wire 82, wire 81 and wire 51 to operate the starter motor 27 in the usual manner. Thereafter when the key 6 is released it will be returned automatically in well known manner to its first position to keep the motor running.

When the circuit breaker 25 disrupts the current a high tension current is induced in the secondary winding 24 of the coil 22 and fed through wire 69 to the distributor 26 and from there in proper sequence to the spark plugs 61 of the motor M.

When the driver leaves the vehicle the key 6 of the switch S¹ is turned back to the position shown in FIG. 1 to stop the motor after which the key 6 is removed from this switch. The key 9 of the switch S² is then turned back to the position shown in FIGS. 1, 3 and 4 and removed from this switch. The driver may, in addition, lock the doors of the vehicle.

The above described construction and arrangement of an ignition system embodying the present invention prevents, or at least tends to prevent, the theft of a vehicle in which it is installed. Anyone attempting to steal the vehicle would first have to break into the car and then try to start the motor from the instrument panel with a duplicate key or by the use of a so-called jumper wire to bypass the starter-and-ignition switch customarily used for this purpose. These attempts of course would fail because of the necessity of first operating the starter-and-ignition switch S² to close its portion of the primary ignition circuit.

When the motor is to be started by the switch S², the key 9 is inserted in this switch and turned in a clockwise direction from the position shown in FIGS. 1 and 4 to a first position shown in FIGS. 6 and 9 to close the secondary ignition circuit (see particularly FIG. 9). This permits the current from the battery 20 to flow through wire 50, solenoid switch 28, wire 81, red wire 17, switch element 7 of the switch S², blue wire 19, primary winding 23 of the coil 22, wire 48, circuit breaker 25 and to the ground at 54. This lights the pilot light 40 and puts the ignition system in condition for a motor start by the switch S² from the motor compartment of the vehicle.

The key 9 is then advanced to a second position to start the motor. This permits the current from the battery 20 to flow through the wire 50, solenoid switch 28, black wire 18, switch element 7 of the switch S², red wire 17, wire 81, and wire 51 to operate the starter motor 27. Thereafter when the key 9 is released it will be returned automatically in well known manner to its first position to keep the motor running.

The provision of a starter-and-ignition switch (the switch S²) in the motor compartment of a vehicle is particularly advantageous to a person who is servicing the motor and the ignition or other units associated therewith. To have such a switch within reach, and capable of independent operation, eliminates the necessity of going to and from the instrument panel to start and stop the motor or of requiring the assistance of a helper for that purpose which has heretofore been the case.

FIG. 10 shows my device mounted in the motor compartment 42 of a front-engine vehicle, the device D being secured to the front side of the fire wall 44.

FIG. 11 shows my device mounted in the motor com-

partment 42' of a rear-engine vehicle, the device D being secured to the rear side of the fire wall 44'. In this type of vehicle the lid or cover 70 of the motor compartment 42' is generally locked as indicated at 71 by a key 72.

It will be apparent from the foregoing description that the present invention, in co-operation with a conventional or other type ignition system, provides two ignition circuits, herein designated a primary ignition circuit and a secondary ignition circuit, which are interconnected and thus used conjointly in the operation of the ignition system.

10 The invention further provides two starter-and-ignition switches (S¹ and S²) both of which are included in the primary ignition circuit (FIG. 8) and one of which (the switch S²) is included in the secondary ignition circuit (FIG. 9).

15 Furthermore both starter-and-ignition switches S¹ and S² must be operated to close the primary ignition circuit as shown in FIG. 8 to permit the motor to be started by the switch S¹ while the switch S² may be operated independently to close the secondary ignition circuit as shown in FIG. 9 to permit the motor to be started by the switch S².

I claim:

20 1. In a motor-vehicle ignition system, in combination, ignition components including a battery, a solenoid switch, a transformer coil, a circuit breaker, a distributor and a starter motor; a main ignition circuit including said components; a main key-operated starter-and-ignition switch by which said main circuit is controlled; a second ignition circuit including said components and by-passing said main switch; and a second key-operated starter-and-ignition switch which may be operated to break said main circuit and by which said second circuit may be rendered operative independently of said main switch.

25 2. In a motor-vehicle ignition system, in combination, ignition components including a battery, a solenoid switch, a transformer coil, a circuit breaker, a distributor and a starter motor; a main ignition circuit including said components; a main key-operated starter-and-ignition switch by which said main circuit is controlled; a second starter-and-ignition switch comprising a fixed element, four terminals carried by said fixed element, and a co-operating key-operated rotatable element which is provided with three contact points that are adapted to be rotated in the path of said terminals to connect the latter element with different combinations of said terminals; and conductors connecting said terminals with said main circuit to establish a second ignition circuit which by-passes said main switch, said second ignition switch being associated with both of said circuits to be adapted to be operated to make-and-break said main circuit and to render said second circuit operative independently of said main switch.
